FOREIGN PATENT DOCUMENTS

CN 308519855 * 3/2024

Primary Examiner — Paula Allen Greene(74) *Attorney, Agent, or Firm* — Daniel M. Cohn; Howard M. Cohn(57) **CLAIM**

The ornamental design for wireless speaker with phone stand, as shown and described.

DESCRIPTION

FIG. 1 is a perspective view of a wireless speaker with phone stand showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1; and,

FIG. 11 is a speaker and stand separated view thereof.

The broken lines depict portions of the wireless speaker with phone stand that form no part of the claimed design.

The dot dash broken lines surrounding the portions of the wireless speaker with phone stand in FIG. 1 and illustrated in the enlarged views of FIGS. 9 and 10 and form no part of the claimed design.

1 Claim, 11 Drawing Sheets(56)
